UNITED STATES PATENT OFFICE.

FREDERICK G. SULTZBACH, OF LANCASTER, PENNSYLVANIA.

GAME APPARATUS.

1,169,886.

Specification of Letters Patent.

Patented Feb. 1, 1916.

Application filed March 17, 1914. Serial No. 825,321.

To all whom it may concern:

Be it known that I, FREDERICK G. SULTZBACH, a citizen of the United States, residing at Lancaster, in the county of Lancaster 5 and State of Pennsylvania, have invented new and useful Improvements in Game Apparatus, of which the following is a specification.

This invention relates to game apparatus; 10 and it has for its primary object the provision of an educational device of this character which while being designed however to afford amusement to the players will thoroughly encourage proficiency in the arts 15 and science of spelling and stimulate the desire to ascertain the meaning of the words formed during the progress of playing the game.

A further object of the invention is the 20 provision of game apparatus which will be especially interesting and instructive to school children while preparing their lessons and one which may be employed in connection with a primer or instruction book, 25 and the latter used so that the children may readily receive correct constructions and definitions of the words spelled and defined.

A still further object of the invention is the provision of game apparatus which will 30 operate to permanently strengthen the minds and memory by causing the player while operating the device to make use of the eyes, ears and hands.

With these and other objects in view, the 35 invention consists of certain novel features of construction, combination and arrangement of parts, as will be hereinafter described and claimed.

In the accompanying drawings: Figure 40 1 is a perspective view of the device, showing a number of splints arranged on the playing surface so as to form a simple word; and Fig. 2 is a transverse section through the device, showing the manner of securing the 45 splints to the board when the device is not in use.

The device consists of a board 1, which may be constructed of any suitable well known material such as cardboard, papier-mâché, rubber, leather, cloth or woven material, wood fiber, glass cement, gutta-percha, celluloid, tin aluminum, metal or any other composition of matter and suitably formed upon the board are outer rows of fields or 50 fonts of vertical passages 1 and beside each of these passages and formed on the board 55

by printing, engraving, or painting thereon is a letter of the alphabet, each of said rows being equal to the entire alphabet, as clearly illustrated in Fig. 1. Extending parallel with the first or other rows of passages are intermediate rows of similar passages 2, which will be hereinafter referred to as the building field or fonts of the structure. The passages 1 and 2 are designed to receive the end 60 of splints as shown in Fig. 1 and according to the selection of the word by the player and in turn of the respective players the splints are adapted to be applied in selected 65 passages upon the playing surface. The letters of the alphabet along one of the outer rows of passages 1 are arranged with such 70 regard to the corresponding letters of the alphabet on the other companion rows of numbers 1, so that the passages 1 of one row 75 are aligned transversely of the board with the mating passages of the other outer row and also with the passages of the intermediate rows of passages 2. In thus arranging the letters of the alphabet the transverse rows of 80 passages will possess determined value throughout the entire playing surface of the board. The arrangement is also such that a player occupying a position adjacent to one of the rows will have an unobstructed view 85 of the letters of the alphabet of the row next adjacent the other player or opponent.

Extending longitudinally over the playing surface of the board is an unequal number of flexible devices, such as strings into 90 which the playing splints may be interwoven and held in place, as shown in Fig. 2 when the game or device is not in use and in this manner the splints may be properly held against loss.

In playing the device a number of the splints are divided equally among the players and at the option of the players it is determined as to the nature or formation of the words to be formed. The five fonts 100 allow the players to choose at will a letter with which to begin the word selected. The playing of the game may be governed by rules so as to cause considerable thinking on part of the players. No word of the same 105 formation and meaning can be scored more than once thus causing the player to continually seek a new word. However, it is not believed to be necessary to set up the arrangement of any definite or preferred 110 rules as to the playing of the game as the rules may be formed among the players.

In selecting words to build from, the players may select the words or preferred objects and for instance in the selection of a simple word, the first player places one of the 5 splints in any one of the passages 2 forming the building fonts. The next player proceeds to build from the letter or letters previously arranged upon the said building field or fonts. If the first player places one 10 of the splints in a passage in the building field or fonts in line with the letter "O", the next player places one of the splints in one of the passages in transverse alinement with the letter "N", he would score, but the players 15 may continue completing as follows: A simple word may be changed to the plural as "boy" to "boys" or "man" to "men" and receive one splint from each player; a simple word may be changed to a compound word, 20 as "tin" to "tin-pan" and score and receive one splint from each player. A simple word may be changed to the opposite as "man" to "woman" and score and receive one splint from each player. A simple word may be 25 changed to the derivative word, as "cave" to "concave" and receive one splint from each player, or the player seeing letters "cave" occupied by a corresponding number of splints may complete a word such as "excavate" and score receiving two splints from 30 each player for prefix and suffix.

A word may be challenged by players in turn before the splints are removed, such opportunity should be given the players by 35 inquiring if satisfied, thus giving chance to correct. If correction is not perfected, the next player may do so and score. The player's challenges are entitled to proof by consulting the dictionary. After the player has 40 definitely placed a splint upon the playing surface he cannot change or remove the same therefrom except when scoring. The number of splints contained in the hand of each player may determine the winner of the 45 game. It is desirable that the players insist on the formation of a record, so as to readily ascertain the words scored and thereby avoid the formation of the same

word twice. The player scoring removes all splints of his word or words complete.

A game apparatus as contemplated in the foregoing will be found extremely useful in the development of minds of children; it is instructive and amusing and is obviously designed to assist young children when 55 playing in competition to each other to increase their vocabulary and to correctly explain the meanings of each of the words formed. The scope of the game is such as to arouse enthusiasm in the art of spelling, 60 as the words are built entirely by hand and again written and then defined, the construction and meaning are placed permanently on the memory. For school children it will be helpful toward familiarizing them 65 in the construction and meaning of the words in spelling lessons or other branches of study and as previously stated in playing the game the players make use of a primer or other book as they are permitted to open 70 the book to choose the necessary classification of words. Such manner of selecting the words from a classification will also tend to encourage concentration and association and avoid unnecessary confusion arising 75 from too large a field in which the players may attempt to work in.

I claim:—

The herein described game apparatus comprising a board having outer and intermediate longitudinal rows of openings, said openings being also arranged in transverse rows across the board and the openings of the outer rows being respectively lettered, in alphabetical sequence, pieces arranged for 80 insertion in said openings, and flexible members extending longitudinally over the board and arranged to receive said pieces when not in use.

In testimony whereof I affix my signature in presence of two witnesses.

FREDERICK G. SULTZBACH,
